UNITED STATES PATENT OFFICE.

RICHARD F. SCHIELE, OF GLEN ELLYN, ILLINOIS.

COMBINED CIGAR LIGHTER AND LAMP.

Application filed May 17, 1923. Serial No. 639,681.

My invention relates to improvements in a combined cigar lighter and lamp and relates particularly to a device of the kind described in which the cigar lighter unit may 5 be detached from the lamp at will.

Another object of my invention is to provide a device of the kind described in which a single switch contact member is used to energize either the cigar lighter or the lamp, 10 as desired.

The invention has among its other objects the production of a device of the kind described, which is neat and attractive in appearance, simple, convenient, compact, 15 durable, reliable, efficient and satisfactory for use wherever found applicable.

Many other objects and advantages of the construction herein shown and described will be obvious to those skilled in the art 20 from the disclosures herein given.

To this end my invention consists in the novel construction, arrangement and combination of parts herein shown and described, and more particularly pointed out in the 25 claims.

In the drawings, wherein like reference characters indicate like or corresponding parts,

Fig. 1 is a longitudinal vertical section 30 taken through my device;

Fig. 2 is a top plan view of the cigar lighter unit;

Fig. 3 is a section taken substantially on line 3-3 of Fig. 2;

Fig. 4 is a fragmentary detail showing the bayonet joint between the cigar lighter unit and a part of the lamp assembly;

Fig. 5 is a fragmentary sectional view 40 similar to that shown in Fig. 1 but illustrating a modified form thereof;

Fig. 6 is a side elevation of the switch block shown in Fig. 5;

Fig. 7 is an elevation of a part of the lamp element cooperating with the switch block 45 shown in Fig. 6;

Fig. 8 is an end view of the switch block; and

Fig. 9 is an end view of the part shown in Fig. 7.

In the drawings, wherein I have illustrated the preferred embodiment of my invention, 1 indicates a wind shield, or panel, upon which is mounted my improved cigar lighter 2 and lamp 3. The lamp and cigar 55 lighter are so connected as to form a unitary assembly, and a universal joint 4 is carried

by the assembly, the same adapted to be mounted at an opening through the wind shield so that universal movement of the assembled lamp and cigar lighter is permitted. 60 The lamp 3 may be of any desired style or shape and is carried at one end of a metal tube 5 which extends through the universal joint 4. The other or inner end of the metal tube 5 is provided with a recess 6 to receive 65 a pin 7 to form a bayonet joint, and adjacent the recess 6 there is formed through the body of the tube 5 an opening 8, said opening being offset at its ends to slidably receive a pin 9 and form a bayonet joint 70 therewith.

A block of insulating material 10 is slidably insertable into the inner end of the tube 5, as shown more particularly in Fig. 1, said block having an axial bore therethrough to receive a contact member 11 at the end thereof and having a radial aperture therethrough to receive the pin 9. The contact member 11 is connected by a lead 75 wire to the lamp.

It is obvious that as the pin 9 is moved longitudinally in the slot 8, the block 10 carrying the contact 11 will be moved longitudinally of the tube 5. A knob 12 of any size and shape, and preferably of metal is arranged to carry a heating element 13 at one end thereof, said element being adapted to be heated sufficiently so as to be capable of igniting the end of a cigar or the like. 85 A portion of the knob 12 is made tubular so as to slidably receive the end of the tube 5, as shown in Fig. 1, and this tubular part of the knob is provided with an axial bore therethrough to permit of the reception of the tube 5. 90

The inner or contact end 14 of the heater element 13 extends within the axial bore 15 of the knob. A switch block 16 is slidable within the axial bore 15 of the knob and carries a contact member 17 centrally therethrough so that it may contact with either the contact 14 of the heater element or with the contact 11 of the lamp. 95

A compression spring 18 normally maintains the contact of the switch block 16 in 105 engagement with the contact 11, as shown. A lead wire 19 from a battery or the like is extended through an elongated transverse opening 20 through the side wall of the knob and is connected to the contact member 17. 110

The knob 12, as has been heretofore stated, is preferably of metal and a wire 21 is

grounded thereto by means of a clip 22, or the like, the other end of said wire leading to the battery. Longitudinally elongated openings 23 are formed through the tubular wall of the knob 12 and through which are adapted to extend arms 24 of a switch bar carried by the switch block 16 so the switch block may be manually moved, against the pressure of the spring 18, to engage the contact of the heater element 13.

The pin 7, slideable in the slot 6, normally locks the knob upon the tube 5, but whenever it is desired to use the cigar lighter the knob is partially rotated and may then be withdrawn as a unit together with the switch block and the lead wires to the point where it is to be used.

In order to heat the element 13 it is necessary that the switch bar 24 be moved toward the contact 14. The compression spring maintains the switch block in contact with the lamp contact member and automatically breaks the cigar lighter circuit when the switch is released. The pin 9 permits of manually moving the contact 11 to its "on" or "off" position as desired so as to control the lamp.

In the form shown in Figs. 5-9 inclusive, the tubular part 5' corresponds to the part 5 shown in Fig. 1. The end of the part 5' has a bayonet joint recess 6' formed at its inner end, and a pair of circumferentially spaced radial notches 26 and 27, respectively, are formed in said end adjacent the recess 6', as shown more particularly in Figs. 7 and 9, one of said notches, the notch 26, as shown, being somewhat deeper than the notch 27.

The cigar lighter unit 2' comprises a knob 12' having an axial bore therethrough to slidably receive the notched end of the tube 5, as shown in Fig. 5, and has the heater element 13' inserted into one end, as in the previous modification.

A switch block 16' is slideable within the bore of the knob 12' and has the contact member 17' extending therethrough. The contact 11' for the lamp 3 is fixed within the bore of the tube 5' and is adapted to be engaged by the contact 17' of the switch block 16'. The inner end of the switch block 16' is provided with a projecting part or point 28 cooperatively engageable within the notches 26 and 27. When the point 28 is in the notch 26, the contact 17' will engage with the fixed contact 11' and when the point 28 is in the notch 27 the contact 17' will be out of engagement with the contact 11'.

The compression spring 18' normally presses the switch block 16' toward the fixed contact 11', and in order to limit the movement of the switch block in this direction there is a pin 30 extended inwardly of the knob 12' and engageable in a longitudinally extending slot in the periphery of the switch block and serving as a stop for said block.

The switch block 16' is preferably made of bakelite or other insulating material and when it is desired to ignite a cigar, the entire cigar-lighter unit 2' carrying the switch block and lead wires may be released from the bayonet joint 6-7 and then the switch block 16' pressed toward the contact 14' to heat the element 13'. The compression spring automatically releases the contact member 17' from the contact 18' as soon as the manual pressure is released, whereupon the unit may be again locked into the bayonet joint until the point 28 comes into contact with the notches 26 or 27, as the case may be, depending upon whether it is desired to have the lamp lighted or not.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a device of the class described, a pair of electrical instrumentalities mounted on opposite ends of a tube, means for adjusting the distance apart of said instrumentalities, a switch movable axially of said tube to selectively actuate one or the other of said instrumentalities when the instrumentalities are mounted at less than a predetermined distance apart and to actuate only one of said instrumentalities when mounted at a distance apart greater than said predetermined distance.

2. In combination, a lamp, a cigar lighter, contacts carried by each of said members, a single switch member intermediate said contacts and selectively operable to energize said lamp or said lighter, and means for automatically releasing said switch member from its energizing engagement with the contact of said lighter.

3. In a device of the class described, a pair of electrical instrumentalities mounted on opposite ends of a tube, means for adjusting the distance apart of said instrumentalities, a switch movable axially of said tube to selectively actuate one or the other of said instrumentalities when their spacing is less than a predetermined amount, resilient means normally holding said switch out of engagement with one of said instrumentalities and manually operable means adapted to move said switch against the pressure of said resilient means into engagement with said instrumentality, said resilient means operating to hold the switch in engagement with the other of said instrumentalities only when the spacing of said instrumentalities is less than said predetermined amount.

4. In combination, a lamp, a lighter removably carried thereby, each of said members having an electrical contact, a movable contact member engageable with either of said contacts, means for normally maintaining said movable contact member in engagement with the lamp contact, and means for manually moving said last-mentioned contacts apart.
5. In combination, a lamp, a lighter detachably connected thereto at one end, each of said members having an electrical contact, a movable contact member carried by said lighter and engageable with either of said contacts, manually operable means for moving said movable contact out of engagement with the lamp contact, and a spring for normally maintaining said movable contact into engagement with said lamp contact and automatically releasing it from engagement with said lighter.
6. In combination, a lamp adapted to be mounted on a panel and having a part projecting therethrough, a lighter having a knob handle with a tubular part engageable with the projecting part of said lamp, means for detachably connecting said knob and lamp, said knob and lamp each having an electrical contact arranged to lie within said tubular part, a movable contact member slidable within said tubular part to engage
- with either of said contacts, manually operable means for moving said slidable contact member into engagement with the contact of said lighter, resilient means for releasing said slidable contact from said last-mentioned engagement and pressing it into contact with the contact of said lamp, and manually operable means for varying the distance between said movable contact and the lamp contact.
7. In combination, a lamp having a tubular part provided with a pair of spaced notches at the end thereof, one of said notches being of greater depth than the other, a lighter detachably mounted upon said tubular part, said lighter and tubular part each having an electrical contact, a switch member slidably carried by said lighter and engageable with either of said contacts and provided with a projecting part engageable in either of the notches at the end of the tubular part, whereby a partial rotation of said switch member will seat its pointed projection into one of said notches to engage with the lamp and a further rotation of said switch member will seat it in the other of said notches to throw the contacts out of operative engagement.
- In testimony whereof, I have hereunto signed my name.

RICHARD F. SCHIELE.
